UNITED STATES PATENT OFFICE.

MILTON H. KNAPP, OF JACKSON, MICHIGAN.

DENTAL APPARATUS.

SPECIFICATION forming part of Letters Patent No. 369,114, dated August 30, 1887.

Application filed January 13, 1887. Serial No. 224,194. (No model.)

To all whom it may concern:

Be it known that I, MILTON H. KNAPP, of Jackson, in the county of Jackson and State of Michigan, have invented new and useful 5 Improvements in Dental Apparatus; and I do hereby declare that the following is a full, clear, and exact description thereof, reference being had to the accompanying drawings, which form a part of this specification.

10 This invention relates to certain new and useful improvements in dental apparatus.

The invention has for its object the construction of an apparatus especially designed for dental use during the process of filling or 15 examining teeth. Ordinarily the "rubber dam" is placed in the mouth of the patient; but the mouth-mirror is held in the hand of the operator, his assistant, or is secured to the chair or table. Thus, should the patient change 20 the position of the head, the focus is destroyed and the mirror has to be again adjusted.

The invention consists in the construction 25 of a chin-piece, in an adjustable mouth-mirror, in an adjustable magnifier, and in the construction, arrangement, and combination of the various parts, all as more fully hereinafter set forth.

Figure 1 is a perspective view of my improved device. Fig. 2 is a diagram showing 30 same as secured to the patient.

In the accompanying drawings, which form a part of this specification, A represents a chin-piece, preferably of metal, although other material may be employed, if desired. This 35 chin-piece is provided with a laterally-projecting slotted flange, B, in which is adjustably secured a post, C.

D is the mouth-mirror, which is connected by a flexible arm, E, to the head of the stand- 40 ard or post. This flexible arm I preferably construct of alternate single and double links a b, respectively clamped together with ball-and-socket joints, thus providing a universal arm by means of which the mouth-piece can 45 readily be adjusted to the desired position in the mouth of the patient.

F is another post or standard, adjustably secured in the slotted flange B, and to this post a magnifying-glass, G, is attached by 50 means of a flexible arm, H, preferably constructed like the arm E, hereinbefore described.

If desired, the post C may be secured in a slotted link, J, adjustably secured in the slotted flange B.

The chin-piece is provided with a "bridle," 55 K, by means of which the device is secured to the head of the patient.

By the employment of a device of this character wherein the support of the mirror and glass are attached to the chin of the patient, to the operator can readily adjust the apparatus so that no movement of the head of the patient will destroy the focus, and thus leaving the free use of both hands in the performance of his work. The chin-piece not only acts as the 65 support, as described, but it also serves as a "dam-holder," obviating the employment of weights and other appliances now generally used.

There are many circumstances connected 70 with dentistry wherein this device can advantageously be employed, either in part or in whole, that will readily present themselves to the mind of the practical dentist.

What I claim as my invention is—

1. In a dental apparatus, a chin-piece provided with suitable attaching-bridle, combined with a mirror connected with said chin-piece, substantially as and for the purposes described.

2. In combination with a chin-piece, a mouth-mirror adjustably secured to said chin-piece by means of a flexible arm, substantially as and for the purposes set forth.

3. In combination with a chin-piece, a magnifying-glass adjustably secured to said chin-piece by means of a flexible arm, substantially as and for the purposes specified.

4. In combination with a chin-piece, A, an adjustable post, C, the mouth-mirror D, and 85 a flexible arm E, substantially as and for the purposes described.

5. The combination, with a chin-piece, A, carrying an adjustable post, F, of a magnifying-glass, G, and flexible arm H, substantially 95 as and for the purposes set forth.

MILTON H. KNAPP.
